UNITED STATES PATENT OFFICE.

FRED. BORNEMANN, OF SAN FRANCISCO, CALIFORNIA.

CHILD'S FOLDING CARRIAGE.

SPECIFICATION forming part of Letters Patent No. 450,362, dated April 14, 1891.

Application filed September 19, 1890. Serial No. 365,555. (No model.)

To all whom it may concern:

Be it known that I, FRED. BORNEMANN, a citizen of the United States, residing in the city and county of San Francisco, State of California, have invented an Improvement in Children's Folding Carriages; and I hereby declare the following to be a full, clear, and exact description of the same.

My invention relates to that class of children's carriages which are adapted to be folded into small compass for easy transportation and to be expanded again for use.

My invention consists in the novel constructions and arrangements of parts herein-after fully described, and specifically pointed out in the claims.

The object of my invention is to provide a simple carriage of this class adapted to be readily folded and unfolded, and which, when expanded for use, will be stiff and rigid enough for all purposes and when folded will occupy but small space, whereby it may be readily carried about.

Referring to the accompanying drawings for a more complete explanation of my invention, Figure 1 is a perspective view of my carriage, showing it open. Fig. 2 is a detail of the back frame and adjustable head-piece. Fig. 3 is a view of my carriage, showing it folded.

A are the side frames of the carriage, made up of suitable horizontal and cross bars. B are the floor-frames, made up of similar bars. These are hinged at their outer ends by the 35 hinges *a* to the lower bars of the side frames, and they are hinged together at their inner or adjacent sides by the hinges *b*. The hinges *a* are so arranged as to permit the floor-frames to fold inwardly and upwardly between the 40 side frames, and the hinges *b* are so arranged as to permit the upward folding of the adjacent ends of the floor-frames.

C are the seat-frames. These are hinged at their outer ends to the side frames by hinges 45 *a'*, and they are hinged together at their adjacent edges by the hinges *c*, and these hinges *a'* and *c* are so arranged as to permit the inward and upward folding of the seat-frames between the side frames and the upward folding 50 of said seat-frames at their adjacent edges similarly to the folding of the floor-frames.

D are the seat-front frames. These are hinged by the hinges *d* to the forward edges of the seat-frames, whereby the said front frames may be turned from a vertical position, 55 in which they extend downwardly from the seat to the floor-frames, to a horizontal position, in which they extend forwardly from and in the horizontal plane of the seat-frames. These front frames are also hinged together 60 by the hinges *d'* at their adjacent edges, whereby said frames may bend upwardly, when in a horizontal position, in a like manner as the seat-frames bend upwardly. It will now be seen that the entire frame of the carriage is 65 jointed in its longitudinal center, whereby it may fold on said line.

E is the back frame, hinged to the upper rear end of one of the side frames by the hinges *e* and having on its other end slots *e'*, 70 which engage catches on the upper end of the other side frame. This back frame is therefore adapted to extend across between the two side frames and when relieved of the catches to be turned inwardly upon its hinges 75 between the side frames.

F are the forward wheels, and G are the rear wheels. The forward wheels are carried by the lower ends of arms *f*, which extend upwardly and are pivoted at *f'* to the front of 80 the said frames. The rear wheels are carried by the lower ends of arms *g*, which are pivoted at their upper ends at the points *g'* to the rear ends of the side frames, and these arms *g* are so bent outwardly as to carry their 85 wheels into planes beyond the planes of the forward wheels, whereby said wheels in turning to a closed position do not interfere with one another.

The pivoted arms *f* and *g* of the wheels are 90 locked in an operative position by means of guides *H*, into which one edge of said arms fits, said guides being carried by the lower bars of the side frames at their forward and rear ends, and they are held in these guides 95 by means of the stop-lugs *I*, which are carried by and project from the outer sides of the floor-frames, and which, when the floor-frames are horizontal, extend outwardly and bear against the other edges of said arms forward and back, as shown.

J is an adjustable head-piece, preferably

upholstered, as shown. This head-piece is hinged at its lower end to the back frame and is adapted to engage catches j with its upper end. Limiting-chains j' adjustably connect the upper end of the head-piece with the upper end of the back frame, so that said head-piece may be turned to different angles to permit of a reclining position of the occupant of the carriage.

10 If desired to regulate the foot-rest to the different lengths of legs of the children, an adjustable frame may be used. K is this adjustable foot-frame, consisting of two frames centrally hinged by hinges k , so as to bend upwardly. The outer edges of these foot-frames are connected with the outer edges of the side frames by means of hinges L , the pintles l of which are removable, so that said foot-frame, when raised to a higher position, may be held at its rear ends and hinged in this position by the pintles passing through the half of the hinge carried by the foot-frames into any of a vertical series of holes x in the ends of the front-board frame.

15 The forward ends of the foot-frames are hinged to the forward ends of the side frames in any vertical position by means of eyes or holes x' on said foot-frames fitting over any of a vertical series of hooks x^2 on the side frames.

20 To understand the operation of the carriage, we will suppose that it is in an expanded condition ready for use. Now to fold it we close up the upholstered head-piece onto the back frame. We then release the back frame from its catches and turn it inwardly between the side frames. We then raise the seat-front frames to a horizontal position; but before this is done, if the foot-frames K are present and are in an elevated position they are released and dropped down onto the floor-frames, to which they are hinged, as described. Now the whole carriage is bent at its longitudinal center, its several frames bending upwardly and approaching each other until they all lie substantially parallel in vertical planes and against one another, the several hinges permitting this folding. The folding of the floor-frames removes the stop-lugs I from the pivoted carrying-arms of the wheels, and the forward wheels are now turned backwardly and upwardly, their arms moving about their pivotal upper ends, and the rear wheels are also moved about their arms forwardly and upwardly, so that the whole carriage is in a compact space and small compass. To open it again the wheels are turned downwardly to proper position, their arms passing into the guides H on the side frames.

25 The floor-frames are then bent to a horizontal position, whereby their stop-lugs I come in behind the edges of the arms, and so lock them, holding the wheels positively rigid. The seat-frames are bent horizontally. The seat-front frames are bent downwardly, so as to rest upon and stiffen the floor-frames, and the back frame is then turned between the

side frames, whereby the whole vehicle is stiffened and is ready for use.

Having thus described my invention, what I claim as new, and desire to secure by Letters Patent, is—

1. In a folding carriage, the combination of the side frames, the divided and hinged floor-frames, the divided and hinged seat-frames, and hinges connecting the outer ends of said floor and seat frames with the side frames, whereby they may be folded together, substantially as herein described.

2. In a folding carriage, the combination of side frames, centrally-hinged floor-frames hinged at their outer ends to the side frames, centrally-hinged seat-frames hinged at their outer ends to the side frames, and the centrally-hinged seat-front frames hinged at the forward end of the seat-frame, substantially as herein described.

3. In a folding carriage, the combination of the side frames connected by intervening hinged and folding frames and the swinging back frame between the rear ends of the side frames, said back frame being hinged at one end and having its opposite end engaged by catches, substantially as herein described.

4. In a folding carriage, the combination of the side frames, the centrally-hinged floor and seat frames hinged at their outer ends to the side frames, the centrally-hinged seat-front frames hinged to the seat-frames, and the swinging back frame between the rear ends of the side frame, substantially as herein described.

5. In a folding carriage, the combination of the side frames, the swinging back frame between their rear ends, and the adjustable head-frame hinged to the back frame and provided with catches and limiting-chains for regulating its position, substantially as herein described.

6. In a folding carriage, the combination of the side frames and the vertically-adjustable foot-frames between them, hinged together at their longitudinal center and hinged at their outer ends to the side frames, substantially as herein described.

7. In a folding carriage, the combination of the side frames, the centrally-hinged foot-frames, and removable hinge-joints between the outer ends of the foot-frames and the side frames, whereby the foot-frames may be vertically adjusted, substantially as herein described.

8. In a folding carriage, the combination of the side frames, the centrally-hinged foot-frames, the seat-front frames, and the means for adjustably connecting the foot-frames, consisting of the hinges with removable pintles, the holes in the seat-front frame, the eyes in the front frames, and hooks on the side frames, substantially as herein described.

9. A folding carriage comprising the side frames, the centrally-jointed floor and seat frames hinged to the side frames, the centrally-jointed seat-front frame hinged to the

seat-frame, the vertically-adjustable foot-frame, the swinging back frame, the wheels, the arms carrying the wheels and pivoted to the side frames, and the locks for said arms 5 when extended, consisting of the guides on the side frames and the stop-lugs on the floor-frame, substantially as herein described.

In witness whereof I have hereunto set my hand.

FRED. BORNEMANN.
